ACCORDION STAND

Joseph A. Mooney, Paterson, N. J.

Application September 23, 1949, Serial No. 117,333

9 Claims. (Cl. 84—376)

1

This invention relates especially to a stand for supporting an accordion. While I am aware of the fact that attempts have been made in the past to design stands for this purpose, I have not, in many years of experience as a player of an accordion, seen or heard of any satisfactory stand for such a musical instrument a great many of which weigh from 25 lbs. and up, mostly above. Hence the practice has been to lug these heavy instruments by strong straps which is objectionable in many ways, for example, the weight and use of the instrument causes the straps to be very tiresome on a player's shoulders, and the straps injure and rumple up the player's clothes, also if, as happens many times, a player has to change quickly from the accordion to another instrument or vice versa, such as the piano, time is lost in the shift which is disadvantageous. All these and other objectionable features of the straps are overcome by my new stand which has many advantages wherein it has a base or platform of water resisting plywood on which the player can stand or sit in a chair. This base or platform also acts as a baffle in transmitting and improving the tone of the instrument. The base is also made so it is rigid when in operation but can be quickly folded up for transportation by hand or otherwise. The base carries supporting means to which an accordion can be easily and quickly attached or detached. The supporting means being so constructed that the usual straps may be kept on the instrument if desired as it may be necessary in some cases to take the accordion for a short time and into some place where a stand would not be necessary.

My new stand allows complete freedom of the player's shoulders, arms and body while playing which is essential to get the best results since they are relieved of the weight of the instrument which is very important to young players.

Another great advantage is that the player can lightly rest his chest against the instrument to feel the vibration without the objectionable features mentioned. Still a further advantage is that the stand is very quickly and easily adjustable so the instrument can be played standing up or sitting down which is advantageous for children, students, teachers and professional personnel. The entire stand can be easily and quickly assembled or disassembled and folded up for transportation and its weight is only about 20 lbs. which is advantageous.

Other advantages will be apparent from a reading of the following specification taken in connection with the annexed drawings wherein

2

Figure 1 is a front elevational view of the stand.

Figure 2 is a view of the top part of Figure 1 in a raised position.

5 Figure 3 is a plan view of the stand.

Figure 4 is a side view of the holder per se for holding the accordion.

Figure 5 is a view of the union between two of the standard parts.

10 Figure 6 is a side view of the locking means used to hold the two parts of the base together.

Figure 7 is a plan view of a part used in holding an accordion in the holder.

Figure 8 is a side view of Figure 7.

15 In the different views taken wherein like numbers refer to corresponding parts, B is a base preferably made of water resisting plywood, which is made up preferably in two parts which are 1 and 2 that are fastened together by a piano-type hinge 3 which is located in the bottom side of the parts 1 and 2 so as to not to interfere with the bottom frame surface. The two parts 1 and 2 are preferably held together on opposite sides by sliding bolt structures 4 and 5. Preferably 20 each of the bolt structures have flanges 6 and 7 that pass over the edges of the boards 1 and 2 so the devices 4 and 5 may be fastened to the boards 1 and 2 on their edges and tops, by screws 8. Attached to the base portion 1 by the screws 9 is a support 10 which has a centrally located hole to receive a support member 11 preferably in the form of a pipe that has its upper end slotted at 12, one of these slits being indicated in Figures 1 and 5. This slotted end of the member 11 is threaded at 13 to receive an internally threaded locking sleeve 14. Through this sleeve passes a rod or tube 15 the lower end of which extends into the tube 11. In the upper end of 15 is fastened as by set screws 16 a collar 17. The collar 40 17 has a pair of ears or lugs 18 to which are pivoted at 19 brace rods or tubes 20 and 21. A description of one of these suffices for both. Fastened to the base portion 1 at opposite corners thereof are studs 22 and 23 and pivoted to these 45 studs at 24 and 25 are adjusting rods 26 and 27. The lower end of these rods are provided with circular notches 28 to receive a positioning latch 29 whereby the tube 20 may be moved downwardly over the rod 26 to any adjustable position. As shown in the drawing, Fig. 1, the tube 20 is 50 made in two parts connected by a turnbuckle 30 which is used so as to take up all the lost motion or slack between the tube 20 and the rod 26. As shown in the right hand brace of Figure 1 the 55 turnbuckle is turned 90° from the one shown in

the left hand brace. In Figure 3 the turnbuckles 30 are not shown as they may or may not be utilized depending on the construction of the positioning means 28 and 29. It is noted that the tube 11 is provided with surface knurls 31 so that the tube 11 may be gripped at the knurls and screwed into or out of the base member 10 for the purpose of assembly or disassembly.

To the upper end of the pipe or rod 15 is fastened a member 32 to receive a pair of plates 33 and 34 that are fastened thereto as by screw studs 35. Positioned between the plates 33 and 34 is a holder 36 somewhat arcuate in shape and having therein an arcuately positioned slot 37 to receive locking bolts or studs 38 which pass through the plates 33 and 34 one of which for example 33 is threaded to receive the wing-nut studs 38, which when tightened up, act to fasten the holder 36 in any arcuate position. The holder 36 has upstanding lugs 39 and 40 with seats 41 thereon to receive an accordion 42 only the lower end of which is illustrated in Figure 4. Adjacent the lower part of the lug 40 is a recess 43 to receive the belt or strap holder and the end of belt 8 that usually is attached to the accordion, especially those of the larger and heavier types. The accordion 42 is held between the lugs 39 and 40 by a set screw 44 that engages the positioning plate 45 shown more in detail in Figures 7 and 8. The positioning plate 45 preferably has a pair of dowel pins 46 for locating it in the lug 39. This positioning plate 45 is provided to accommodate accordions of different widths between the lugs 39 and 40. It is shown in Figure 8 that the dowel pins 46 are of considerable length so as to allow the adjusting screw 44 to move the positioning plate 45 into locking position with the accordion.

Fastened to the lower portion of the front lug 39 as by screw studs 47 is an arm 48 preferably made of suitable material, preferably metallic, having some resilience. At the outer end of the arm 48 is a receptacle 49 having a locking member 50. The arm 48 extends at an acute angle with respect to the holder 36 so that the receptacle 49 will be in a position to receive the lower end of the accordion keyboard.

It may be noted in passing that in mounting the accordion on the holder 36 suitable pads 51 such as felt may be used to prevent marring the outer surface of the accordion.

From what has been said it will be seen that I have designed an accordion stand which is, as has been pointed out, relatively light in weight yet rigid and especially useful for supporting an accordion in any desired vertical or arcuate position to obtain all of the advantages which have been mentioned.

It is obvious that certain of the minor details may be changed without departing from the spirit of my invention and the scope of the appended claims.

Having thus described my invention what I claim is:

1. A supporting stand for an accordion including, a relatively large base to receive the player, a relatively small support member carried on the base, an upwardly extending tube fastened to the support member, a rod preferably hollow slidably carried by said tube and extending above it with means for locking the rod in any adjusted position, a collar fastened to the rod near its upper end, a pair of adjustable brace rods pivotally attached to said collar and extending, each to a point near opposite corners of the same edge

of the base, a pair of plates fastened to the upper end of the slidable rod and on opposite sides thereof, a holder having an arcuately shaped portion positioned between the upper portions of said plates, the said portion having an arcuate slot therein to receive clamping means carried by said plates, said holder having upwardly extending lugs at its opposite ends to receive and support the main part of an accordion, and an arm having some flexibility fastened at one end to one of the lugs and extending in a direction at an acute angle to said holder and having a receptacle to receive the end of the accordion key board.

15 2. A supporting stand for an accordion as set forth in claim 1 further defined in that the upper end of said tube is slotted so the slotted portions may be forced into engagement with said rod, the tube having screw threads on at least the slotted portion and an internally threaded sleeve slidable on the rod over the end of the tube to engage said screw threads and draw the slotted ends thereof into gripping contact with said rod to hold it in any adjusted position.

20 3. A supporting stand for an accordion as set forth in claim 1 further defined in that said tube is screw threaded into the support member while the tube has a knurled surface preferably adjacent its upper end whereby the tube may be quickly removed from its support member, and the base is in parts hinged together, and each brace rod is in two parts one slidable within the other whereby the tube, base and brace rods may be quickly folded up for transportation purposes as described.

35 4. A supporting stand for an accordion as set forth in claim 1 further defined in that at least the lug, preferably the one, from which said arm extends carries an adjustable plate, with means for adjusting it as described.

40 5. A supporting stand for an accordion as set forth in claim 1 further defined in that the upper extremity of said rod has an enlargement with flat sides to receive said plates with a screw stud going through said plates and enlargement.

45 6. A supporting stud for an accordion including, a base large enough for a player to stand on, a standard in two slidable parts, one part being fastened to the base while the other has a holder for the accordion arcuately mounted at its top end, the holder having two upstanding lugs to locate the accordion in the holder with means on at least one of the lugs for fastening the accordion in place in the holder, an arm 55 having some flexibility fastened to the holder end away from the player and extending at an angle with respect to the holder toward the position of the player and having a receptacle to receive the end of the keyboard of the accordion and adjustable braces extending, one from each corner of the base on the side opposite that used by the player, to the standard just below the said holder.

50 7. A supporting stand for an accordion as defined in claim 6 further defined in that said braces are provided with turnbuckles so all slack in the regular adjustment is eliminated.

70 8. A supporting stand for an accordion as set forth in claim 6 further defined in that the holder has an arcuate slot extending the greater part of the length of the holder while the lugs have internally located seats to receive the accordion and means attached to the upper, of said two slidable parts and carrying devices passing 75 through said slot to anchor the holder in any

adjusted position over the range of the slot and a recess below the seat on the lug next to the player position to accommodate the accordion strap holder.

9. A supporting stand for an accordion as set forth in claim 6 further defined in that the base is in two parts hinged together so the parts are foldable in a downwardly direction away from the holder with means for locking the two parts together in playing position to increase the rigidity of the base whereby it acts as a baffle

5 board in transmitting and improving the tone of the accordion.
